UNITED STATES PATENT OFFICE

113,625

DESIGN FOR A TABLECLOTH OR SIMILAR ARTICLE

Frances Olga Ferlauto, New York, N. Y.

Application January 17, 1939, Serial No. 82,396

Term of patent 3½ years

To all whom it may concern:

Be it known that I, Frances Olga Ferlauto, a citizen of the United States of America, residing in New York city, in the Borough of Manhattan, county and State of New York, have invented a new, original, and ornamental Design for a Tablecloth or Similar Article, of which the following is a specification, reference being had to the accompanying drawing, forming part thereof, wherein the figure is a plan view of a tablecloth or similar article showing my design.

I claim:

The ornamental design for a tablecloth or similar article, substantially as shown.

FRANCES OLGA FERLAUTO.
